UNITED STATES PATENT OFFICE.

LILLIAN K. ENGLE, OF PHILADELPHIA, PENNSYLVANIA.

FASTENING DEVICE.

1,142,510.

Specification of Letters Patent.

Patented June 8, 1915.

Application filed November 4, 1914. Serial No. 870,174.

To all whom it may concern:

Be it known that I, LILLIAN K. ENGLE, a citizen of the United States, residing in the city and county of Philadelphia, State of Pennsylvania, have invented a new and useful Fastening Device, of which the following is a specification.

My invention consists of a fastener or fastening device for detachably connecting parts of materials, such as garments, which fastener is secured to the material without stitching or other extraneous fastening and can be attached or detached to and from the material without the use of any special tool or mechanism.

It further consists of other novel features of construction, all as will be hereinafter fully set forth.

The annexed drawing and the following description set forth in detail one mechanical form embodying the invention, such detail construction being but one of various mechanical forms in which the principle of the invention may be used.

In said drawings—Figure 1 represents a plan view of one member or form of my novel fastener. Fig. 2 represents a plan view of the coöperating part of the fastener. Fig. 3 represents a plan view of one of the elements of the fastener secured in a fabric. Figs. 4 and 5 represent an edge-view, respectively, of each of the elements of one form of the fastener. Fig. 6 represents a section of the hook-element of the fastener. Fig. 7 represents a plan view of another form of fastener. Fig. 8 represents a plan view of the coöperating mate of the same. Fig. 9 represents a side view of the fastener illustrated in Fig. 7. Fig. 10 represents a section of the fastener illustrated in Fig. 8.

Similar numerals of reference indicate corresponding parts in the figures.

Referring to the drawings, the reference numeral 1 indicates a body-portion, which is illustrated as formed from a flat bar or plate of sheet-metal or similar sheet-material such being the preferred material. Pointed prongs, 2, are formed at the ends of the body-portion and extend inward at both edges of said portion, pointing toward each other and having narrow slits between their inner side edges and the edges of the body-portion. The bar or body-portion disclosed in Figs. 1, 3 and 4, is formed with a swell, 3, at its middle, raised above the level of the

ends of the body and of the prongs. The form illustrated in Figs. 2, 5 and 6, has a tongue projecting laterally from the middle of one edge of the body-portion, to form a hook, 4, one limb of which has an inward hump 5.

In Figs. 7 and 9, a clasp member, 6, is shown as formed upon the face of the body-portion, and in Figs. 8 and 10 is illustrated a tapering and flanged socket, 7, here shown in the middle of the body-portion, which socket can receive the clasp member 6 of the companion fastener to removably lock the parts together.

The prongs are inserted into the material to which the fastener is to be secured and the prongs penetrate the material, as seen in Fig. 3. The form of fastener having the swell in the body-portion is employed together with an opposite fastener having a hook, so that the latter can engage the swell and secure the parts of the material together. The form of fasteners illustrated in Figs. 7 to 10 is secured to the material in the same manner as the previously described form, and the fasteners are detachably connected as above described. The prongs projecting toward each other will secure the fastener against longitudinal movement and hold the same flat against the surface of the material, and the prongs, extending for the major portion of the entire length of the body-portion and forming the narrow slits between them and the edges of the body-portion will clamp the fabric in such slits, and will prevent transverse movement of the fastener upon the surface of the fabric. The prongs are substantially in the same plane as the ends of the body, with their pointed ends suitably extending, if desired, slightly below the body, or angularly, for ease of insertion into the material, whereby the fastener can be quickly and easily secured to the material and without any use of needle and thread or other tools or extraneous means.

The fasteners occupy comparatively small space and admit of being secured within folds or ruffles of a garment to be out of view.

The fastener is preferably formed from sheet-metal, cut out and shaped by stamping or similar process, and, on account of the simplicity of its shape, the fastener can be made at very small expense and in great quantities in comparatively short space of

time. The body-portion can be shaped with varying forms of detachably interlocking fastening means, two forms being here disclosed.

5 Other modes of applying the principle of my invention may be employed for the mode herein explained. Change may therefore be made as regards the features thus disclosed, provided the principles of construction set 10 forth, respectively, in the following claim are employed.

Having thus described my invention, what I claim as new and desire to secure by Letters Patent, is:—

15 A fastening device, comprising a rigid

body portion having a pair of integral prongs extending from each end thereof and longitudinally of the body portion and substantially in the same plane, the ends of the pairs of prongs pointing toward each other, 20 said prongs being separated from the body portion with their inner edges substantially parallel with the edges of the body to form narrow slits in which the material is seated and gripped.

LILLIAN K. ENGLE.
